No. 739,578.

PATENTED SEPT. 22, 1903.

W. H. BECROFT.
TIME CONTROLLED VULCANIZER.
APPLICATION FILED AUG. 21, 1902.

NO MODEL.

UNITED STATES PATENT OFFICE.

WILLIAM H. BECROFT, OF PHILADELPHIA, PENNSYLVANIA.

TIME-CONTROLLED VULCANIZER.

SPECIFICATION forming part of Letters Patent No. 739,578, dated September 22, 1903.

Application filed August 21, 1902. Serial No. 120,490. (No model.)

To all whom it may concern:

Be it known that I, WILLIAM HENRY BECROFT, a citizen of the United States, residing in the city and county of Philadelphia, State of Pennsylvania, have invented a new and useful Improvement in Attachments to Vulcanizers, of which the following is a specification.

My invention consists of an improved time-regulating apparatus, which although capable of being employed in various connections is especially adapted for use in connection with vulcanizers to relieve the steam-pressure thereof at a certain predetermined time, and thus prevent the material under treatment from being overheated and thereby rendered useless.

The invention further consists in the details of construction hereinafter described and claimed.

Figure 1 represents a front elevation of a time-regulating apparatus constructed in accordance with my invention and connected with a vulcanizer. Fig. 2 represents a side elevation thereof. Fig. 3 represents a fragmentary detail view of a portion of the spring-motor. Fig. 4 represents a front view of a modified construction of the spring-motor.

Similar letters of reference indicate corresponding parts in the figures.

Referring to the drawings, A designates a portion of a vulcanizer of familiar construction, and B the gas-supply pipe communicating therewith, and as these parts are of ordinary construction further description therefore is unnecessary. The vulcanizer A is also provided with the steam blow-off valve C, of ordinary construction, with the stem D of which is connected the arm E, the movement of the latter serving to operate the valve.

In the art of vulcanizing various materials, whether for commercial or dental purposes, it is desirable to cut off the supply of gas to the vulcanizer at a certain predetermined time, and to accomplish this I employ a clock or timing device F, so arranged as to actuate means controlling the self-actuating valve G in the pipe B, supplying gas to the vulcanizer, mechanism being also arranged so that upon the closing of the valve G the steam blow-off valve C is opened to allow the escape

of the steam. On the stem of the valve G is a spring, the tendency of which is to close the valve, and I term this a "self-actuating" valve. An arm or member J is also secured to the stem K of said valve and is provided at its outer end with a yoke L, that engages a cam M, turned by the clock, the tendency of the spring H being to hold one limb of the yoke in engagement with the cam M. The operation of this part of my invention is as follows: To operate the vulcanizer, the arm or member J is moved downwardly to the position shown in Figs. 1 and 2, with the yoke engaging the cam M. In moving the arm to this position the valve G is opened, and the position of the yoke relative to the ends of the worm or screw determines the period of time within which the gas-supply will be cut off, it being understood, of course, that as the clock moves the yoke will travel across the outer end of the cam M, and when it reaches the outer end the spring H will throw it to the position shown in dotted lines in Figs. 1 and 2, turning the stem K of the valve to close the latter. When the gas is cut off, the steam blow-off valve is opened, and I accomplish this by means of a motor, conveniently a spring-motor N, that is connected with the arm E of the blow-off valve by chain P. The motor N is provided with an outer movable drum Q, with which end of the chain P is connected, as at R, and when the motor is wound the arm E can be moved into position to close the valve C. Said drum Q is held against turning by means of a catch S, mounted upon a stationary support T, said catch engaging a notch or shoulder U in said drum. The catch is also provided with a projection V, that is situated in the path of the arm or member J, and a spring W serves to hold the catch S engaged with a notch U. The said notch S is provided with a finger X, that engages the drum in the rear to limit the outward movements thereof under the influence of the spring W. Secured to the frame or stationary part T is a guard-arm Z, that extends over the face of the drum Q to hold the chain P in position, and thus prevent the same from flying off and becoming displaced. The spring-motor can be wound by pulling on the chain P, and when the notch U arrives opposite the catch S the spring will

move the notch into engagement therewith to prevent the spring from unwinding. The arm E of the blow-off valve C is then moved to the position shown in Figs. 1 and 2 to close the latter. When the arm or member J is released from the cam M, it moves to the position shown in dotted lines, Figs. 1 and 2, and the projection V of the catch S being in the path thereof said catch is turned on its pivot 5 and disengaged from the shoulder on notch U of said drum. This allows the spring to unwind, and the drum in turning winds the chain P and opens the valve C by means of the arm E.

15 It is of course understood that the particular construction of mechanism for releasing the self-actuating device or valve G is not essential, as I can employ other time-regulating devices, my invention comprising any 20 time-controlling means for releasing such valve, and, further, my invention is not limited to the particular form of motor M for actuating the blow-off valve, as other motors or devices actuated by gravitation can be employed for this purpose, and therefore except 25 in claims for the specific construction my invention is not limited to the particular devices herein shown and described.

In Fig. 4 I show the motor N as provided 30 with a toothed wheel A', that engages a rack B', from which extends a rod C', that connects with the blow-off valve C, as another form of connection between the motor and said valve, a handle D' being employed to 35 wind the motor.

Having thus described my invention, what I claim as new, and desire to secure by Letters Patent, is—

1. In an attachment to a vulcanizer of the 40 character stated, means for supplying heating material to the vulcanizer, and a blow-off valve on the vulcanizer, in combination with a timing device and mechanism connected with said means and valve, whereby by simultaneous or substantially simultaneous action, 45 the heating material may be cut off and the pressure within the vulcanizer relieved.

2. In an apparatus of the kind specified, a vulcanizer having a blow-off valve, a self-actuating valve controlling the pipe supplying gas to said vulcanizer, a timing device controlling the operation of said self-actuating valve, and a motor connected with the blow-off valve of said vulcanizer and adapted to be set in operation by reason of the movement of said 55 self-actuating valve.

3. In an apparatus of the kind specified, a vulcanizer having a blow-off valve, a self-actuating valve controlling the pipe supplying gas to said vulcanizer, an arm or member movable with said valve, a timing device having a cam adapted to engage and release said arm or member, a motor connected with the blow-off valve of said vulcanizer, and means for holding said motor inoperative situated in the 60 path of said arm or member.

4. In an apparatus of the kind specified, a vulcanizer having a blow-off valve, a self-actuating valve controlling the pipe supplying gas to said vulcanizer, an arm or member movable with said valve, a timing device having a cam adapted to engage and release said arm or member, a motor, a catch for holding the same inoperative situated in the path of said arm or member and adapted to be moved by 75 the latter to allow the motor to operate, and a connection between said motor and the blow-off valve of the vulcanizer.

5. In an apparatus of the kind specified, a vulcanizer having a blow-off valve, a self-actuating valve controlling the pipe supplying gas to said vulcanizer, a timing device adapted to permit said valve to operate, a motor, a spring-actuated catch to hold said motor inoperative, a projection on said catch, an arm 80 or member movable with said valve adapted to engage said projection, and a connection between said motor and the blow-off valve of the vulcanizer.

WILLIAM H. BECROFT.
